C. C. SHIPP

REHEATING RADIATOR HOUSING

Filed Sept. 15, 1924

UNITED STATES PATENT OFFICE.

CLARENCE C. SHIPP, OF INDIANAPOLIS, INDIANA.

REHEATING-RADIATOR HOUSING.

Application filed September 15, 1924. Serial No. 737,724.

To all whom it may concern:

Be it known that I, CLARENCE C. SHIPP, a citizen of the United States, residing at Indianapolis, in the county of Marion and

5 State of Indiana, have invented a new and useful Improvement in Reheating-Radiator Housings, of which the following is a specification.

It is old in the ventilating art to provide 10 a box through the outside wall of a house, for the admission of outside air. It is also old to surround the sections of a radiator with vertical walls, open at the top, but connected at the bottom with the wall-box by 15 means of a base-box which fills the space to the floor. This has not been sanitary because the open top allows children and others to deposit apple cores, particles of food, and chewing gum in it, and allows dust 20 and dirt to enter, all of which drop down into the base-box to accumulate and remain where all of the air entering through the wall-box comes in contact and is polluted by it.

25 The object of this invention is to support the radiator from the inner wall of the room in which it is located, instead of on legs reaching to the floor, high enough above the floor to allow room for the bottom of the 30 box-base, which is in the form of a hinged door, to swing down and dump all foreign matter out or to be swept off or scrubbed, if need be, and by such elevation and wall support to make sweeping under the radiator 35 possible and easy.

A further object is to provide a damper in the wall-box and so connect it with said downwardly swinging door of the box-base, that the wall-box damper will always be 40 closed when the box-base door is open, thereby preventing cold outside air from blowing or passing directly into the room through the open base-box door.

45 A further object is to shut off the outside air, as the occasion requires, and pass the cold air which settles next to the floor of the room, through the radiator and its housing, thereby to create a circulation of the air in the room and uniformly heat it.

50 A further object is to provide easy means for manipulating the damper and the box-base door, and for holding their given adjustments.

A further object is to provide means for easy and ready assembly or dismemberment 55 of the various units of my device.

I accomplish the above, and other objects which will hereinafter appear, by the means illustrated in the accompanying drawing, in which—

Fig. 1, is a perspective view of a radiator with my invention installed, the wall-box being partly in vertical section. This view shows the damper closed in the wall-box and the box-base door open. Fig. 2, is a vertical section on the line 2—2 of Fig. 1, except that the wall-box damper is open and the box-base door closed, and Fig. 3, is a perspective view of a wooden frame around the inner end of the wall-box sleeve, to which 70 the flange of the box-base is fastened.

Like characters of reference indicate like parts in the several views of the drawing.

The radiator 4, comprising as many sections as may be required, is supported by 75 any suitable means (not shown) from the outside wall 5 of a building in which a room to be heated is located. Passing through the wall opposite and more or less below the lower end of the radiator is a ventilating 80 opening in which is a box 6, here shown as having storm louvers 7, insect screen 8, and a damper 9, hinged at its upper edge to an offset in the top of the box formed around the top member of a wooden frame 10. The 85 damper closes in an oblique position against a flange 11, across the bottom of the wall-box. The wooden frame 10 extends along the top, bottom and both ends of the wall-box and to this frame a flange 12 of a wall- 90 box base is fastened by screws or nails 13. The wall-box base is here shown in two separable members 14 and 15, for convenience of assembly, which are joined in a lap-joint 16. A door 17 is hinged at its rear edge to 95 the member 14, and when shut closes an opening under the radiator, part of which is formed in member 14 and the rest in member 15.

The base-box as a whole has an up-turned 100 end that telescopes in the lower end of a sheet-metal radiator housing 18, here shown as open on top but as surrounding all but the two end coils of the radiator.

Slotted ears 19, in the upper edge of the 105 base-box, enable the housing and base-box

to be slidingly assembled with stove bolts 20, after which, by tightening the bolts, the assembly will be retained. By making the base-box and the radiator housing each in 5 two separable parts, these parts may be easily removed thereby making access easy to the radiator.

Bolt hooks 30, 30, one at each end of the base-box, are suspended over the bosses 10 formed by the radiator connections, and nuts on their threaded ends outside of the base-box, provide adjustable means for suspending the base-box from the radiator, and holding the stove bolts 20 in their slots.

15 Pivoted to ears 21, extending up from the bottom of the wall-box, is a bent lever 22, the short arm of which is connected by a link 23, with ears on the damper 9. To the long arm of lever 22, a chain 24 is fastened. 20 This chain passes back of an idler pulley 25, thence up to and over an idler 26 on the back of the housing 18, and thence across and through a hole 27 in the front wall of 25 housing 18, and terminates with a handle 28, of such size that it will not pass through the hole. A link of the chain is dropped in a slot, extending down from the hole, which locks the chain. The long arm of the lever 22 is connected with the door 17 by a spring 30 29, which elastically holds the door in closed position when the long arm of the lever is elevated by the chain to the position shown in Fig. 2. The adjustment of the parts is such that in this closed position of the door 35 the damper 9 will be full open, and conversely, when the damper is closed the door will be released and will drop down by gravity to the open position shown in Fig. 1.

It will be observed that a clear space 40 under the base-box is secured, for sweeping; that refuse matter dropped into the upper open end of the radiator housing will be deposited upon the door 17, from which it will drop off or may be swept off when the 45 door is lowered and open.

It is also obvious that the door will never be open to reheat the air next to the floor of the room, except when the outside air is 50 shut-off by the closed damper, and therefore, that the cold outside air must always pass through the radiator housing to be warmed before it is discharged into the room.

The invention is capable of variations in 55 structure and arrangement and I therefore do not limit myself to the precise form here shown, nor any more than is required by the appended claims.

I claim:—

60 1. A vertical radiator housing open at its top, a horizontal wall-box, a box-base connecting the wall-box with the bottom end of the housing, a door in the bottom of the box-base, said door being substantially horizontal when closed and swinging downward- 65 ly and rearwardly upon opening, a spring

normally closing the door, and manually operated means for releasing the action of the spring.

2. A vertical radiator housing open at its top and bottom, and a door hinged on its rear side normally closing the bottom, upon which loose material entering the housing at the top is deposited by gravity and brought into position for easy removal below the housing by swingingly opening the door, 75 automatic means normally closing the door while permitting it always to be manually opened.

3. A vertical radiator housing open at its top and bottom, a wall-box, a box-base 80 telescopically entering the housing and connecting the wall-box with the lower end of the housing, the outer one of said telescoping members having stove-bolts and the inner one having slots in from the end to slidingly receive the bolts, which bolts are then tightened.

4. A radiator, a vertical radiator housing around the radiator open at its top and bottom, a wall-box, a box-base telescopically entering the housing and connecting the wall-box with the lower end of the housing, the housing having stove-bolts and the box-base having end slots to receive the bolts which are tightened after insertion, the box-base 90 being in two longitudinally divided parts, and bolt hooks suspending the box-base 95 from couplings between sections of the radiator.

5. The combination, with a radiator, a 100 radiator housing open at its upper end, an air supply means, a damper in said means, a door hinged below the lower inner wall of the housing and, which in its closed position is substantially horizontal and closes the lower end of the housing, means for simultaneously closing the damper and opening the door, and means for automatically closing the door and for allowing it to be 105 opened manually independently of said simultaneous damper and door operating means.

6. The combination, with a radiator, a 110 radiator housing open at its upper end, an air supply means, a damper in said means, a door hinged below the lower inner wall of the housing and, which in its closed position is substantially horizontal and closes the lower end of the housing, means for simultaneously closing the damper and opening the door, and a spring for automatically 115 closing the door and for allowing it to be opened without closing the damper.

7. The combination with a radiator, a vertical radiator housing open at its top and 120 bottom, a wall-box, a damper in the box, a box-base connecting the wall box with the lower end of the housing, a door in the box-base substantially horizontal when closed and hinged at its rear edge, manually operated 125

means for simultaneously closing the damper and opening the door, and elastic means for automatically closing the door and for allowing it to be opened manually independently of said damper and door operating means.

8. The combination, with a radiator, a vertical radiator housing open at its top and bottom, a wall-box, a damper in the box, 10 a box-base connecting the wall-box with the lower end of the housing, a door in the box-base substantially horizontal when closed and hinged at its rear edge to the box, a bent lever pivoted at the bend, a link connecting one arm of the lever with the damper, elastic means connecting the other arm 15 of the lever with the door and manual means

for shifting the lever to change the positions of the damper and door.

9. A radiator housing, a wall-box, a 20 damper in the wall-box, a box-base connecting the wall-box with the lower end of the housing, a door in the box-base hinged at its rear side to swing downwardly and rearwardly in opening, manually controlled 25 means connecting the door with the damper for simultaneously closing the door when the damper is open and the reverse and elastic means for normally closing the door.

Signed at Indianapolis, county of Marion, 30 State of Indiana, this the 9th day of Sept., 1924.

CLARENCE C. SHIPP.
